UNITED STATES PATENT OFFICE

149,645

DESIGN FOR A TOOL FOR OPENING BOTTLES, JARS, AND THE LIKE

Allan V. Johansen, Lynbrook, N. Y.

Application November 5, 1946, Serial No. 134,515

Term of patent 3½ years

(Cl. D44—29)

To all whom it may concern:

Be it known that I, Allan V. Johansen, a citizen of the United States, residing at Lynbrook, in the county of Nassau, in the State of New York, have invented a new, original, and ornamental Design for a Tool for Opening Bottles, Jars, and the like, of which the following is a specification, reference being had to the accompanying drawing, forming a part thereof.

Fig. 1 is a front elevational view of a tool for opening bottles, jars, and the like, showing my design; Fig. 2 is a side elevational view; Fig. 3 is a rear elevational view; and Fig. 4 is a top plan view of the same.

I claim:

The ornamental design for a tool for opening bottles, jars, and the like, as shown.

ALLAN V. JOHANSEN.
